UNITED STATES PATENT OFFICE

WALTER F. SHETZLINE, OF LOS ANGELES, CALIFORNIA

AUTO WINDOW OPERATING MEANS

Application filed February 17, 1932. Serial No. 593,524.

This invention relates to improvements in window operating constructions and particularly it is designed to be used in conjunction with automobile windows and analogous structures.

An object of the invention is to provide an improved window operating means for effecting a raising or lowering of the window within its frame. The improved construction utilizes as its motive force the partial vacuum developed within the intake manifold of the engine of the automobile and while this source of power for effecting movements of the window within its frame has been used heretofore, the present invention contemplates an improved arrangement for utilizing this source of power.

More specifically an object of the present invention is to provide a window operating mechanism utilizing the vacuum produced within the intake manifold of the automobile engine and to provide a braking or locking construction for locking or holding the window in its adjusted position. The invention contemplates having the braking or locking mechanism automatically operable on operating the window moving mechanism so that when it is desired to adjust the window the braking or locking construction will automatically be released and when the moving mechanism is stopped the braking or locking mechanism will automatically engage.

Another object of the invention is to provide a novel construction for guiding the window in its movements from one position to another and for locking or holding the window in adjusted position. It has been customary to provide suitable felt runners for the glass panes of automobile windows, which felt runners have the tendency to absorb moisture during wet weather. They consequently swell so that during wet weather it is frequently very difficult to open or close the window. The improved construction eliminates this difficulty and also enables the pane to be firmly gripped and held in any position. This feature of the invention may be employed with or without the vacuum operated window moving mechanism.

With the foregoing and other objects in

view, which will be made manifest in the following detailed description, and specifically pointed out in the appended claims, reference is had to the accompanying drawing for an illustrative embodiment of the invention, wherein:

Fig. 1 is a view in elevation, parts being broken away and shown in section, illustrating an automobile door having a window to which the improved mechanism has been applied.

Fig. 2 is a sectional view taken substantially upon the line 2—2 upon Figure 1.

Fig. 3 is a sectional view through a multiple port valve, which may be employed as part of the mechanism.

Fig. 4 is a horizontal section taken substantially upon the line 4—4 upon Figure 1.

Fig. 5 is a vertical section taken substantially upon the line 5—5 upon Figure 1.

Referring to the accompanying drawing, wherein similar reference characters designate similar parts throughout, 10 designates an automobile door hingedly mounted as by hinges 11 and providing the window frame for a glass window 12 which is vertically movable therein. In accordance with the conventional construction, the lower portion of the door provides a pocket which may receive the pane 12 when in its lowermost position and from which the pane 12 may be removed to close the window opening 13. In the bottom of the door 10 and in the bottom of the pocket formed thereby, there is mounted a cylinder 14 within which there is a piston 15. At the end of the cylinder there is rotatably mounted upon a transversely extending pintle 16 a sprocket 17. A ratchet wheel 18 is rigid with the sprocket. A chain 19 is fastened to the piston 15 and extends through the open end of the cylinder over sprocket 17 to a pulley or sprocket 20 which is rotatably mounted on the door near the top of the pocket. The end of the chain is secured to a suitable fitting 21 which embraces the bottom of pane 12 near the center thereof. At the opposite end of the cylinder a suitable conduit 22 leads to a valve generally designated at 23, which may be mounted on the door at any suitable or convenient loca-

tion. The details of this valve construction will be hereinafter described. It is sufficient to state that from this valve there leads a second conduit 24 which may have incorporated in it a detachable coupling 25 or a hose to enable opening of the door, which conduit leads to the intake manifold of the automobile engine. The partial vacuum developed in the intake manifold will likewise be developed within the conduit 24 and when the valve 23 is properly operated will be transmitted to the interior of the cylinder 14. As the opposite side of the piston 15 is exposed to air pressure, it is obvious that the piston will move from right to left as viewed in Figure 1, causing the pane 12 to be elevated by chain 19. On top of the cylinder 14 there is pivotally mounted a pawl 26 engageable with ratchet wheel 18 and urged into engagement with it by spring 27. The opposite end of the pawl is connected to a suitable plunger 28 disposed within a diaphragm cup 29 mounted on top of cylinder 14. A diaphragm formed of rubberized canvas or equivalent impervious but flexible material indicated at 30 has its edges secured near the base of the diaphragm cup. Its center portion is secured to the under side of the plunger 28 and the plunger fits the diaphragm cup with sufficient looseness to enable air pressure to be transmitted to the upper side of the diaphragm. A conduit 31 serves to transmit a vacuum to the diaphragm cup on the under side of the diaphragm 30 to cause the diaphragm to pull the plunger 28 downwardly. This enables the pawl 26 to be caused to disengage ratchet wheel 18. Conduit 31 is a branch conduit from a longitudinally extending conduit 32. This conduit extends longitudinally through the pocket from side to side thereof. At each of its ends there is a pair of collapsible flattened metallic tubes, one pair of which is indicated in Figure 4 by the reference characters 33 and 34. This pair of tubes extends upwardly from conduit 32 to the top of window opening 13 and a similar pair of collapsible flattened metallic tubes extends upwardly from the opposite end of conduit 32 to the top of window opening 13. The pane 12 is slideable between the tubes of each pair and by virtue of the fact that the tubes are formed of metal, such as thin sheet brass or the like, they will not swell in wet weather and bind the glass. They normally tend to expand against the side faces of the glass 12 to frictionally hold the glass in any position. However, when a vacuum is formed within conduit 32, it is also formed within the tubes at each end so that these tubes will be partially collapsed due to the vacuum therein and thus either disengage glass 12 entirely or engage it with such a small amount of force that the friction therewith is negligible. Conduit 32 is connected to valve 23 by means 65 of pipe 36.

The construction of the valve employed will now be described, reference being had particularly to Figure 3. The valve consists of a casing or body 37 within which is rotatable a rotary member 38. This rotary member is operable by a handle 39. The connection for conduit 24 is illustrated thereon, the end of conduit 24 being illustrated. In the rotary member there is formed a bore 40 shown as registering with the port for conduit 24. This bore communicates with an arcuately removed portion 41 of the rotary member. The port for conduit 36 is indicated, the end of this conduit being shown on this figure. The end of conduit 22 is likewise shown, leading from the cylinder. Reference characters 42 and 43 merely indicate passages in the body or casing of the valve leading to the normal air pressure. An arcuately removed portion of the valve or rotary member is also indicated at 44. In the position shown the vacuum formed in conduit 24 is transmitted through bore 40, the arcuately removed portion 41, to conduits 22 and 36. Conduit 22 leads to cylinder 14 and the formation of a vacuum therein causes the window to be elevated. At the same time the vacuum transmitted through conduit 36 causes diaphragm 30 to be depressed to disengage pawl 26 and also causes the tubes at the ends of conduit 32 to be collapsed. With the tubes collapsed and the pawl disengaged, the window is free to be elevated by the piston 15 moving from right to left. When the window has been elevated to the desired height, handle 39 is swung downwardly into a horizontal or intermediate position. In this position the port for conduit 24 is closed and bore 40 registers with the port 43 leading to air pressure, that is the normal air pressure of the atmosphere. This normal atmospheric pressure is thus transmitted through bore 40 to conduits 22 and 36, the arcuately removed portion 41 still uncovering the ports for these conduits. The admission of air pressure to conduits 22 and 36 causes the pressures on opposite sides of piston 15 to become equalized so that the piston will stop its movement. The equalization of pressures on opposite sides of diaphragm 30 enables spring 27 to cause pawl 26 to engage the ratchet wheel 18. Equalization of pressures on the inside and outside of the expandable tubes 33 and 34 enables these tubes to assume their normal condition in which they tend to expand against the window pane 12. The expansive effort is sufficient to create enough friction to frictionally hold pane 12 in adjusted position. In order to lower the window 12, handle 39 is swung into a downwardly inclined position, in which case the rotary member assumes the position indicated in dotted lines upon Figure 3. The arcuately removed portion 41 then establishes communication between conduit 70 75 80 85 90 95 100 105 110 115 120 125 130

24 and conduit 36 only. The arcuately removed portion 44 establishes communication between inlet port 42, allowing for ingress of air, and conduit 22. With this result, 5 pressures within the cylinder on opposite sides of piston 15 remain equalized. The vacuum, however, formed in the diaphragm cup 29 below the diaphragm 30 and within the expandible metallic tubes causes the pawl 10 1c 26 to disengage ratchet wheel 18 and the tubes to disengage or release window 12. Window 12 can then fall or slide downwardly under its own weight into a lower position. It is obvious that by manipulation of the 15 handle 39 the vacuum produced within the intake manifold of the engine may be used to effect a raising or lowering of the window 12, or the holding of the window 12 in any desired position.

20 It is not essential that both the pawl 26 and ratchet wheel be used in the same construction with the expandible flattened tubes 33 and 34. In many instances the expandible flattened tubes are sufficient to hold the window 25 in any adjusted position, in which case the diaphragm cup, pawl 26, ratchet wheel 18, and conduit 31 are dispensed with. In other instances it may be deemed advisable to employ the pawl, ratchet wheel and dia- 30 phragm cup in preference to the expandible tubes. In still further instances both constructions can be used simultaneously as shown. It will also be appreciated that the use of the expandible tubes as guides for the 35 window frame and as locking means for locking the window in any desired position is not restricted to a construction employing the specific elevating mechanism shown. These tubes can be advantageously employed in any 40 construction having a movable pane in which it is desired to produce a weather tight joint with the pane yet permit it to slide when desired.

Various changes may be made in the 45 details of construction without departing from the spirit or scope of the invention as defined by the appended claims.

I claim:

1. In combination with a window frame 50 having a window movable therein, expansi-

ble means mounted upon the frame and normally expanded into engagement with the window to hold the window in adjusted position, said expandible means being capable of being contracted to release the window by 70 the presence of a vacuum, and means for providing a partial vacuum to contract said means.

2. In combination with a window frame, 75 having a window movable therein, a cylinder, a piston exposed to air pressure on one side located within the cylinder, means for forming a partial vacuum on the other side of the piston, means operable by the piston for elevating the window in the frame, a brake for holding the window in elevated position, and vacuum operable means for causing the brake to release the window when a partial vacuum is formed in the cylinder.

3. In combination with a window frame 85 having a window movable therein, a cylinder, a piston exposed to air pressure on one side located within the cylinder, means for forming a partial vacuum on the other side of the piston, means operable by the piston 90 for elevating the window in the frame including a chain connected to the piston and to the window and trained over a sprocket for effecting elevation of the window when the piston is actuated, a ratchet wheel rigid with 95 the sprocket, and a vacuum operated pawl normally engaging the ratchet wheel for holding the window elevated but adapted to disengage it when a vacuum is created.

4. In combination with a window frame 100 having a window movable therein, a cylinder, a piston exposed to air pressure on one side located within the cylinder, means for forming a partial vacuum on the other side of the piston, means operable by the piston for elevating the window in the frame including 105 a chain connected to the piston and to the window and trained over a sprocket, a brake for holding the window in elevated position, vacuum operable means for causing the brake 110 to release the window when a partial vacuum is formed in the cylinder, and means for causing the vacuum operable means to be operated without creating a vacuum in the cylinder.
